UNITED STATES PATENT OFFICE.

SOLON S. CAHILL, OF BRUNSWICK, MAINE.

PUZZLE.

No. 878,187.

Specification of Letters Patent.

Patented Feb. 4, 1908.

Application filed April 16, 1907. Serial No. 368,458.

To all whom it may concern:

Be it known that I, SOLON S. CAHILL, a citizen of the United States, residing at Brunswick, in the county of Cumberland and State of Maine, have invented certain new and useful Improvements in Puzzles; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to new and useful improvements in puzzles and consists essentially in the provision of a grooved way adapted to represent a railway line and, in which groove, blocks representing cars are 20 adapted to be moved, the main groove having a blind spur branching therefrom, the object of the invention being to cause the blocks representing two distinct railway trains headed in opposite directions to pass 25 each other by shifting the cars from the main groove to the blind spur.

The invention is illustrated in the accompanying drawings, in which:—

Figure 1 is a perspective view of the puzzle 30 showing the grooved way and the blind spur branching therefrom and illustrating in perspective two trains of cars headed in opposite directions and Fig. 2 is a cross sectional view through the grooved way and 35 through a car showing the manner in which the latter is guided in the groove.

Reference now being had to the details of the drawings by letter, A designates a board or plate made of any suitable material, 40 either wood or metal, and provided with a straight longitudinal groove B in which the two trains of cars, each with a locomotive, are adapted to be guided and to travel in opposite directions. Leading laterally from 45 said main groove is a blind spur D which terminates abruptly and is of such a length as to allow only two cars or an engine and a car upon the spur at the same time. The

two trains of cars are adapted to travel in the directions indicated by the arrow upon 50 the drawings.

In operation trains of twelve to fifteen cars may be utilized in my puzzle, but for illustration two cars only are contained in each train. Assuming the trains have met 55 and wish to pass each other, the engine and one car of the train going to the right will run on the spur, after which the train going in the opposite direction or to the left is moved forward a sufficient distance to allow said 60 engine and one car to move to the right of the train going to the left. We now have the engine and one car at the rear of the train going to the left. Afterward the train passing to the left advances far enough to 65 allow the engine and cars upon the spur to pass on the main track in the rear of the train going to the left, then the train which is going to the left is backed up and the remaining car of the train going to the right 70 allowed to be run on to the spur, after which the train going to the left may advance and back against the car upon the spur and draw the same on to the main track where it may be reconnected to the train going to the 75 right.

It will thus be seen that, by the provision of a simple and efficient device as shown and described, a puzzle is afforded whereby two trains may pass each other upon a single 80 track.

What I claim to be new is:—

A railway puzzle comprising a plate having an elongated straight groove with a branching groove leading therefrom at an 85 angle and terminating blindly, blocks fitted to move within said grooves, and forming two trains of more than two blocks each, said branching groove being of sufficient length to receive only two of said blocks. 90

In testimony whereof I hereunto affix my signature in presence of two witnesses.

SOLON S. CAHILL.
